UNITED STATES PATENT OFFICE.

WILLIAM L. CARTER, OF CEDAR FALLS, IOWA.

GRATE.

SPECIFICATION forming part of Letters Patent No. 468,033, dated February 2, 1892.

Application filed March 19, 1891. Serial No. 385,649. (No model.)

To all whom it may concern:

Be it known that I, WILLIAM L. CARTER, a citizen of the United States, residing at Cedar Falls, in the county of Black Hawk and State 5 of Iowa, have invented a new and useful Grate, of which the following is a specification.

This invention relates to improvements in grates for furnaces, &c.; and the objects in view are to provide a grate of cheap and simple construction that may be easily operated, and which when so operated will thoroughly shake the ashes therefrom into the ash-drawer.

Other objects and advantages of the invention will appear in the following description, 15 and the novel features thereof will be particularly pointed out in the claims.

Referring to the drawings, Figure 1 is a perspective of a grate constructed in accordance with my invention. Fig. 2 is a vertical 20 longitudinal section. Fig. 3 is a plan, the grate being removed. Fig. 4 is a bottom plan view of the grate, the same being in detail.

Like numerals of reference indicate like parts in all the figures of the drawings.

1 indicates the ash-pit, into which may be slid the usual ash-drawer, (not shown,) and the same has its rear end rounded and has mounted thereon the cylindrical fire-pot-supporting ring 2.

30 A cross-bar 3 spans the ash-pit in front of the supporting-ring 2, and upon the same and to the wall of the ash-pit is secured the ring 4, the outer edge of which is provided with a series of teeth 5. At intervals upon bearing-pins 6, located under the ring 4, are mounted loose rollers 7. In longitudinally-opposite bearing-brackets 8 there is mounted for rotation in bearings 9, formed therein, a shaft 10, which extends outside the ash-pit, is there 35 provided with an operating-crank 11, and inside the same, under and within the ring 4, is provided with a gear-wheel 12.

The grate proper consists of a cylindrical collar or frame 13, the lower edge of which is toothed, as at 14, and the upper edge of which is provided with a flared inclined flange 15, the inner edge of which extends beyond the inner surface of the cylindrical frame 13 and is provided at intervals with tangentially-disposed ribs 16. The inclined flange 15 loosely fits the fire-pot-supporting ring 2, while the cylindrical frame or collar 13 fits within the

ring 4, and its teeth engage the teeth of the gear-wheel 12, and also are designed to ride over and be supported upon the loose rollers 55 7. The cylindrical frame of the ring is provided at diametrically-opposite sides with bearing perforations 18, in which there is journaled a shaft 17. At each side of the shaft 17 similar shafts 19 are journaled in bearings 60 20, the three shafts being provided with polygonal-shaped disks 21, between which extend opposite series of blades or fins 23, extending from the sides of the cylindrical frame 13 of the grate. The central shaft of the grate 65 is provided at one end with a star-wheel 24, which engages in the teeth of the ring 4, and at its opposite end is provided with a gear 25, which engages and drives the corresponding gears upon the shafts 19 at each side of the 70 central shaft 17.

In operation the crank at the front of the ash-pit is rotated, and through the medium of its gear, which engages the lower toothed edge of the grate-frame, said grate-frame is rotated, 75 and in so doing the teeth of the star-wheel of the central shaft of the grate engage the teeth of the grate-ring 4, and thus said central shaft is rotated and through the medium of its gear transmits motion to the gears of 80 the two side shafts, and in this manner the entire bottom of the grate is revolved, so that a most thorough agitation of the fire may be had and all ashes quickly deposited into the ash-pit. It will be noted that the flange 15, 85 revolving with the grate, being inclined and provided with tangentially-disposed ribs, serves to gather and direct the usual wall of ashes that surround the fire to the center of the grate, and from thence into the ash-pit. 90

Having described my invention, what I claim is—

1. The combination, with an ash-pit having a toothed ring mounted therein and a shaft rotatably supported and extending under said ring, of a grate-frame having a lower toothed edge, a gear mounted on the shaft and engaging the toothed edge of the frame, a series of shafts rotatably mounted in the frame, gears connecting the corresponding ends of the 95 same, and a gear mounted on one end of one of the shafts and engaging the ring of the ash-pit, substantially as specified.

2. The combination, with the ash-pit, the

toothed ring supported therein, a crank-shaft having a gear mounted below the ring, and a series of loose rollers also mounted below the ring, of a cylindrical grate-frame having a 5 toothed lower edge loosely fitting within the ring and having its teeth engaging the gear of the crank-shaft and resting upon the rollers, an inclined flared flange located at the upper edge of the grate-frame and having tangentally-disposed ribs, a main central shaft journalized in the grate-frame, terminating at one end in a star-wheel, engaging the teeth of the ring of the ash-pit, opposite side shafts, disks mounted on the free shafts, and gear-wheels mounted on the corresponding ends of the shafts and engaging each other, substantially as specified.

3. The combination, with an ash-pit and a revoluble grate mounted therein and consisting of an open frame or collar having ribs 16, of a series of shafts mounted in the grate below the same, a series of disks mounted on the shafts within the opening of the frame or collar, means for rotating the grate-frame, and means for rotating the shafts simultaneously and by the same mechanism, substantially as specified.

In testimony that I claim the foregoing as my own I have hereto affixed my signature in presence of two witnesses.

WILLIAM L. CARTER.
